UNITED STATES PATENT OFFICE.

RALPH V. HEUSER, OF WATERBURY, CONNECTICUT, ASSIGNOR TO ROESSLER & HASS-LACHER CHEMICAL CO., OF PERTH AMBOY, NEW JERSEY, A CORPORATION OF NEW YORK.

PRIMARY BATTERY.

1,015,735.

Specification of Letters Patent. Patented Jan. 23, 1912.

Application filed April 25, 1911. Serial No. 623,169.

To all whom it may concern:

Be it known that I, RALPH V. HEUSER, citizen of the United States, and resident of Waterbury, in the county of New Haven 5 and State of Connecticut, have invented certain new and useful Improvements in Primary Batteries, of which the following is a specification.

This invention relates to primary batteries and particularly a form of cell in 10 which sodium amalgam is used as an essential element and to form the positive electrode.

The objects of my invention are to produce an improved form of sodium amalgam battery that will be highly effective, 15 comparatively simple in construction and very desirable for some classes of work by reason of its compact form; to provide a cell 20 that may be used as either a wet or dry cell. The battery is further constructed so that the same can be easily taken apart and reassembled as for renewing the elements when occasion requires.

With the above and other minor objects 25 in view my invention resides and consists in the simple and novel construction of battery shown upon the accompanying sheet of drawings forming a part of this specification, upon which similar characters of reference denote like or corresponding parts throughout the several figures, and of which,

Figure 1, shows a central vertical longitudinal section through my novel form of sodium amalgam cell complete and, Fig. 2, 35 is a horizontal cross section of the battery cell shown in Fig. 1 and taken on line 2—2 of that figure.

Upon the drawings 5 indicates a pan having 40 cross ribs 6 in its bottom portion to form a rest for a battery jar 7 made of metal seated therein. A cover 8 surrounds the jar and serves to inclose the pan 5 which 45 is normally filled with water when the cell is working. The lower part of the jar 7 is perforated to admit water from the pan, and used for the purpose of wetting the copper oxid depolarizer 9 contained within the 50 lower part of the jar. Above this layer of copper oxid I provide a thin insulating film of hydraulic cement 10, carbonate of lime or a diaphragm of an organic origin such as 55 unsized paper or cloth and together with a rubber ring 11 serve to insulate the negative

metal electrode containing the copper oxid from the positive electrode arranged above and formed of sodium amalgam.

The metal sodium amalgam is represented by the numeral 12 and as shown is placed upon the insulator 10 and within the lower part of the cylindrical porcelain lining 13 contained within the jar. A metal plate 14 is secured upon the sodium amalgam and to it is fastened a post 15. A pair of special shaped shells 16—16 are placed one upon another to form an annular pocket intermediate thereof and the porcelain 13. This pocket is filled with a cotton packing 17 which together with the shells pack the sodium amalgam in the porcelain cylinder. Upon this packing is laid a grooved ring 18 intermediate of which, and the cover 19, is placed a compressed spring 20 that bears down upon the ring and packs the sodium amalgam to hold the same in place, that is, with its lower face in good contact with the diaphragm. The cover is secured to the flange of the jar by means of short screw bolts 21, one of which may be provided with 25 an extra nut and employed as one of the terminals 22 of the battery. The second terminal 23 is located central of the cover and is properly insulated therefrom. A short wire 24 connects this terminal 23 with the post 15 thus forming a connection with the positive or sodium amalgam side of the cell, while the binding post obviously connects with the metal jar itself in which the copper oxid is placed representing the negative pole of the battery.

Having thus described my invention what I claim and desire to secure by Letters Patent is:

1. In a battery of the class described the combination with a metallic jar representing the negative electrode, of a layer of suitable material in direct contact with said jar as a depolarizer, of an adjacent upper layer of sodium amalgam representing the positive electrode, a suitable insulation between the two, and terminals connected to each of said electrodes.

2. In a battery of the class described, the combination with a metallic jar representing the negative electrode, of a layer of suitable material in direct contact with said jar as a depolarizer, of an adjacent upper layer of sodium amalgam representing the positive electrode, a suitable insulation between the two, and terminals connected to each of said electrodes.

two, and means for effecting a pressure upon the sodium amalgam while in action.

3. In a battery of the class described, the combination with a perforated jar, a pan in which the jar is contained and designed to hold water to penetrate the jar, sodium amalgam within the jar, copper oxid also contained within the said jar, an insulation between the sodium amalgam and copper oxid, and terminals for the sodium amalgam electrode and the metal electrode containing the copper oxid.

4. In a battery of the class described, the combination of a jar, a filling of copper oxid within the jar, a covering of insulating material thereover, a layer of sodium amalgam contained therein but insulated therefrom, a spring to compress the sodium amalgam in place, and terminals connected with the sodium amalgam electrode and the metal electrode containing the copper oxid.

5. In a battery of the class described, the combination with a jar, a filling of copper oxid within the jar, a covering of insulating material therefor, a layer of sodium amalgam also contained therein, an insulating cylinder within the jar and surrounding the sodium amalgam, a plate covering the sodium amalgam, and a spring bearing upon the plate in contact with the sodium.

6. In a battery of the class described, the combination of a jar, a filling of copper oxid within the jar, a covering of insulating

material thereon, a layer of sodium amalgam also within the jar but insulated therefrom, a plate upon the sodium amalgam, a post secured to the plate, and a spring to hold the plate into contact with the sodium amalgam.

7. In a battery of the class described, the combination of a jar and cover, a filling of copper oxid within the jar, a layer of sodium amalgam, an insulating cylinder within the jar surrounding and above the sodium amalgam, a plate upon the sodium amalgam, a post secured to the plate, a terminal insulatively attached to the cover, an electrical connection between the post and terminal, and a second terminal for the copper oxid side of the battery.

8. In a battery of the class described, the combination of a jar, a filling of copper oxid within the jar, a covering of insulating material thereon, a layer of sodium amalgam, a plate upon the sodium amalgam, a packing above the plate, a ring upon the packing, a spring intermediate of the ring and cover to press the plate against the sodium amalgam.

Signed at Waterbury in the county of New Haven and State of Connecticut this 18th day of April A. D., 1911.

RALPH V. HEUSER.
